UNITED STATES PATENT OFFICE.

ROMAN ABT, OF BÜNZEN, SWITZERLAND, ASSIGNOR OF ONE-HALF TO
OTTO GRUNINGER, OF NEW YORK, N. Y.

LOCOMOTIVE.

SPECIFICATION forming part of Letters Patent No. 339,831, dated April 13, 1886.

Application filed January 16, 1886. Serial No. 188,731. (No model.)

To all whom it may concern:

Be it known that I, ROMAN ABT, a citizen of the Republic of Switzerland, residing at Bünzen, in said Republic, have invented a new and useful Improvement in Locomotives and Railway-Vehicles, of which the following is a specification.

The development and construction of railroads in mountainous countries has up to the present time been very costly, because of the comparatively small gradients which can be mounted by the ordinary adhesion locomotive. By making steep gradients the cost of construction could be greatly reduced; but the ordinary adhesion locomotives could exert but small traction-powers on account of their own large absorption of power. The safety of operating adhesion lines with steep gradients is also very small.

In order to cheapen the construction of railway-lines in mountainous countries, and also to haul large loads, and to enable locomotives and trains to be operated with the same degree of safety on steep gradients as is obtained with the regular adhesion locomotives on ordinary railway-lines, it has been proposed to construct a locomotive with a pinion or pinions adapted to engage a rack-rail secured parallel with and between the track-rails, and it is to this class of locomotives that my invention relates.

The invention consists in the combination, with the adhesion and supporting axles and wheels of a locomotive, of a frame consisting of parallel side portions having at their ends independently adjustable boxes fitting the axles, and a pinion or pinions journaled in said frame and adapted to engage a toothed rack-rail, all as more fully hereinafter described, and pointed out in the claims.

The invention also consists in novel combinations of parts, whereby the power necessary for operating the rack-rail pinion or pinions is transmitted from a cylinder or pair of cylinders, preferably separate from and independent of the pair of cylinders whereby the adhesion axles and wheels are operated.

The invention also consists in the novel construction of a pinion which may be employed with a railway locomotive or car for engaging

with a rack-rail, and which is composed of a number of toothed disks arranged side by side and having an elastic or yielding connection with their shaft, whereby the disks may be allowed to turn slightly one relatively to another, and will all come to a proper and equal bearing upon the teeth of the rack-rail. This part of the invention is applicable both to the driving-pinion of a locomotive and to a pinion supported upon a railway-car, and through which the power of a brake may be applied for stopping the car.

The invention also consists in the novel manner of coupling two pinions upon the locomotive together, so that the teeth of one pinion will engage the teeth of the rack-rail slightly in advance of those of the other pinion and the driving-power will be exerted more uniformly and with less jerks and shocks and greater safety. This novel manner of coupling two pinions together may be employed in connection with pinions which consist each of a solid disk or toothed wheel, and is also applicable to pinions severally composed of two or more toothed disks arranged side by side and with their teeth stepped relatively to each other, so that the teeth of the several disks will successively engage with the teeth upon the rack-rail.

The invention also consists in the combination, with a pinion-shaft and a pinion composed of toothed disks arranged side by side, of flanges between which the disks are confined, and one or each of which carries a cylindric brake-drum.

The invention also consists in a particular construction and combination, in the pinion, of a hub or center, two or more disks encircling the same side by side, and springs whereby the disks have an elastic or yielding connection with the hub or center and through it with the shaft.

The invention also consists in the combination, with a rack-rail composed of toothed bars arranged parallel side by side, with spaces between them, and a locomotive having a pinion or pinions engaging the rack-rail, of a snow-plow carried by the locomotive and having projections which enter the spaces between the parallel bars of the rack-rail, and

serve to keep said spaces clear from obstructions.

In the accompanying drawings, Figure 1 is a longitudinal sectional elevation of the parts 5 of a locomotive which are necessary to illustrate my invention. Fig. 2 is a transverse vertical section upon the plane of the dotted line $x-x$, Fig. 1. Fig. 3 is a transverse section upon the plane of the dotted line $y-y$, Fig. 1. Fig. 4 is an axial section through one 10 of the driving-pinions, upon a larger scale. Fig. 5 is a section upon the plane of the dotted line $z-z$, Fig. 4. Fig. 6 is an axial section of the pinion, having its toothed disks connected 15 with the shaft by an elastic or yielding connection of different construction, but also included in my invention. Fig. 7 is a section upon the plane of the dotted line $**$, Fig. 6. Fig. 8 is a sectional view upon the plane of 20 the dotted line $1-1$, Fig. 7. Figs. 9, 10, 11 respectively represent portions of the three disks, of which one of the driving-pinions is composed and portions of the rack-rail bars with which these disks engage, the teeth of 25 the disks and rack-rail bars being shown in the positions which they occupy simultaneously relatively to each other; and Figs. 9^a, 10^a, 11^a respectively represent portions of the three toothed disks of the pinion, which is 30 coupled with the first pinion, and portions of the rack-rail bars with which these disks engage, showing them in the positions which they occupy relatively to each other at the moment, and also relatively to the positions 35 shown in Figs. 9, 10, 11.

Similar letters of reference designate corresponding parts in all the figures.

Although some features of my invention are applicable to a locomotive adapted to be 40 employed with a rack-rail of the ordinary form, the invention is more particularly intended for locomotives to be used in connection with a rack-rail such as is shown in my United States Letters Patent No. 284,790, dated September 11, 1883, and which is composed of two or more parallel toothed bars arranged side by side, with their teeth stepped or arranged out of line with each other. I have, in Figs. 1 and 2, shown portions of such 45 a rack-rail, A, the several bars a of which are secured side by side by bolts a' to chairs A^* , and have their teeth arranged out of line with each other, or stepped relatively to each other.

In illustrating my invention I have only 55 shown the adhesion and supporting axles B of the locomotive, and the adhesion and supporting wheels B', which are upon these axles, and a portion, C, of the adjacent boiler. In order that the pinions, which are hereinafter described, shall engage at a uniform and proper 60 distance with the rack-rail A, they must be supported independent of the springs of the locomotive. As here represented, the pinion-shafts D, of which two are shown, are supported by a frame represented as consisting 65 of two parallel bars, E, which have at their ends independently-adjustable boxes e , fitted

to the axles B, and held in place in the side pieces of the frame E by keys e' . In this way the frame E is supported from the axles directly, and is entirely independent of the springs of the locomotive. In like manner the frame might be supported from the axle-boxes of the axles B B, or from any other part of the engine, uninfluenced by the springs which support the superposed locomotive structure. 75

The pinion-shafts D D are here shown as arranged near the ends of the frame E, and, as here represented, are journaled in boxes $e^2 e^3$, the caps e^3 of which are held in place by bolts e^4 passing & through a cross plate or bracket, e^5 , bearing upon or attached to the upper side of bars E. The two pinions F F, which are carried upon the shafts D, may be operated from the main cylinders of the locomotive, which are shown 85 in dotted lines at G G, Fig. 2; or they may be operated by separate cylinders. (Shown by dotted lines G' G' in Fig. 2.) A single pinion F, or two or more pinions F coupled together and engaging with the rack-rail A, may be employed for propelling a locomotive on steep gradients either alone or with the assistance 90 of the adhesion drivers. As here represented, the pinion-shafts have upon them cranks D', which are coupled by parallel rods D', as is usual in locomotives, and the cranks D' of one pinion-shaft—in this instance the rear one—are operated by connecting-rods D³ from rocker-arms D⁴, which are shown in Figs. 1 and 2. The cranks D', at opposite ends of the pinion-shafts, should be set on the quarter relatively 100 to each other, as is usual in locomotives, and therefore the rocker-arms D⁴ D⁴, at opposite sides of the locomotive, are connected with and project from an inner rock-shaft, D⁶, and a 105 tubular rock-shaft, D⁶, surrounding the inner rock-shaft, both said shafts being journaled in bearings b on the main side frames, H, of the engine. The two rock-shafts D⁶ D⁶ are provided with upwardly-projecting arms D', 110 with which the pistons in the cylinders G' are connected by rods D⁸.

As before described, the rack-rail A is composed of parallel bars a , three being here shown arranged side by side and having their teeth stepped or set out of line relatively to each other. The pinions F are each composed of toothed disks arranged side by side and corresponding in number with the bars of the rack-rail, three being here shown, and also 120 have their teeth stepped or set out of line relatively to each other. In order that the teeth of each pinion shall engage uniformly with the toothed bars of the rack-rail, it is desirable to employ between the pinion-disks and their shaft an elastic or spring connection, which will enable any one of the disks to turn very 125 slightly relatively to its shaft and relatively to the other disk or disks.

In Figs. 4 and 5 I have shown a construction 130 and combination of the pinion and shaft which provides for this slight turning of the several disks relatively to each other.

Upon the shaft D is secured a hub or center,

I, which, as represented, is secured to the shaft by a key, *c*, and has a cylindric exterior. The toothed disks *d d' d''*, which compose the pinion, are bored out to snugly fit on the hub 5 or center I, and are arranged side by side thereon. As here represented, the disks are held side by side, without, however, clamping them together, by means of flanges *f*, which are held on the hub or center I by bolts 10 *f'* passing through them, and, as here shown, these flanges *f* have constructed integral with them cylindric grooved brake-drums *f''*, to which a brake may be applied. Of course one flange only might have such a brake-drum *f''* constructed with it.

The toothed disks *d d' d''* are bored out to snugly fit the hub or center I, and they are connected therewith by springs *g*, which are best shown in Fig. 5. Each of these springs 20 consists of a U-shaped piece of steel, made semicircular at the inner end, and having at its ends which are presented outermost inward projections *g'*, which are separated uniformly by a slight space, and which form 25 spaces to limit the elasticity of the spring. These springs rest in grooves or spring-seats *g''*, formed in the periphery of the hub or center I, and their outer ends project slightly beyond the circumference of the hub or center 30 and enter notches *g'''*, formed in the toothed disks *d d' d''*. Consequently it will be seen that each disk may turn relatively to the hub or center when it encounters resistance until the projections *g'* of the springs come together, 35 and thereafter the disk will be locked solidly to the hub or center when continuing to turn in the same direction.

In Figs. 6, 7, and 8 I have represented a modified construction of the pinion-disks *d d' d''*, 40 and means of giving them an elastic connection with the shaft, which is also included in my invention.

Referring to Figs. 6, 7, and 8, I designate the hub or center, composed of two members, 45 secured to the shaft *E* by a key, *c*, and having flanges *f*, which embrace between them the disks *d d' d''*. The disks and flanges *f* have in them holes *h*, parallel with the axis and of considerable size, and in these holes are flat 50 bars *h'*, the opposite ends of which are screw-threaded and provided with nuts *h''*. The bars *h'* are set radial to the disks *d d' d''*, and the spaces in the holes or bores *h* on opposite sides of the bars are filled in with segmental blocks 55 of metal, *h'''*, and interposed blocks of india-rubber or similar elastic substance, *h''''*. The flat bars *h'* are secured against turning by pins or keys *h''''*, inserted in their ends and in the flanges *f*, and those portions of the metal 60 blocks *h'''* which have a bearing in the flanges *f* have greater projection than the portions of the blocks which project into the disks *d d' d''*, and a greater projection than those metal blocks *h'''* which are arranged within the disks, as shown 65 in Fig. 8. The rubber blocks *h''''* are, however, made of a size to snugly fill the spaces between the flat bar *h'* and the circumference of the

bores or holes *h*, as also shown in Fig. 8. Consequently it will be seen that the disks *d d' d''* can yield circumferentially relatively to each 70 other and to the flanges *f* to the extent of movement allowed by the blocks *h'''*, the rubber *h''''* being compressed so that the disks *d d' d''* will come to a bearing on the interposed metal blocks *h'''*. 75

The arrangement of the pinion-disks *d d' d''* with their teeth stepped or out of line relatively to each other will be best understood from Figs. 9, 10, and 11, which represent the three disks of one pinion, and from these 80 figures it will be seen that the teeth of the pinion-disks come to a bearing in succession one after another upon the teeth of the rack-rail bars *a*, the pinion being supposed to rotate in the direction indicated by the arrow. 85

In Figs. 9^a 10^a 11^a I have represented the three disks of the second pinion, which is coupled with the first, and which are supposed to rotate also in the direction indicated by the arrow. 90

By comparing Figs. 9 and 9^a or Figs. 10 and 10^a and Figs. 11 and 11^a, it will be understood that the several disks of the one pinion engage with the toothed bars of the rack-rail slightly in advance of the corresponding disks 95 of the other pinion, and therefore the action of the pinion-disks of the two pinions upon the bars of the rack-rail is rendered more uniform and the driving is effected without shock or jar. 100

As I before stated, that feature of my improvement which consists in a pinion composed of a number of disks having an elastic or spring connection with their shaft is not confined to a driving-pinion and locomotive, 105 as such pinion might be provided on one or more cars, together with some brake device acting through the pinion to check the motion of the train in case of any accident to the pinion mechanism of the locomotive. 110

In order to enable the pinions to work properly in the rack-rail *A* in winter weather, I have represented a snow-plow, *J*, at each end of the locomotive and attached to the frame *E*. This plow should have projections 115 which will enter the spaces between the parallel bars *a* of the rack-rail, and will clear them from snow or ice to such depth as to enable the pinions to engage properly with them.

The plow or plows *J* on the locomotive 120 serve to clear away from between the bars of the rack-rail snow, ice, and any dirt or pebbles which may become fixed between them.

It is advantageous to arrange the rock-shafts *D⁵ D⁶* one within the other, because of the 125 compactness thereby afforded. They may, however, be otherwise arranged, it being necessary only that they be capable of turning one independently of the other.

I have here shown the number of parallel 130 bars *a* of the rack-rail as corresponding to the number of disks in the pinion *F*, because such would be the case on the maximum gradients in a line of railway.

To secure economy of construction, the rack-rail may have a less number of bars on the easier gradients, and a less number of the pinion-disks would then be active.

5 The reduction in the diameter of the tires of the adhesion-wheels of the locomotive, which is due to wear or turning them off, will of course lower the pinion and its supporting-frame, and alter the working relation 10 of the pinion to the rack-rail, and this may be corrected by adjusting the bearings of the frame on the axles.

What I claim as my invention, and desire to secure by Letters Patent, is—

15 1. The combination, with the adhesion and supporting axles and wheels of a locomotive, of a frame consisting of parallel side portions E, having at their ends independently-adjustable boxes fitting the axles, and a pinion or pinions 20 journaled in said frame and adapted to engage with a toothed rack-rail, substantially as herein described.

25 2. The combination, with the adhesion and supporting axles and wheels of a locomotive, of a frame supported independently of the springs of the locomotive, a shaft journaled in said frame and carrying a pinion for engaging a rack-rail, a crank on said shaft, and a rock-shaft and rod, through which motion 30 is transmitted to the crank on the pinion-shaft, substantially as herein described.

35 3. The combination, with the adhesion and supporting axles and wheels of a locomotive, of a frame supported independently of the springs of the locomotive, a shaft journaled in said frame and carrying a pinion and cranks set at an angle relatively to each other, and two rock-shafts having arms connected by rods with the cranks on the pinion-shaft, 40 and through which motion is transmitted for operating the pinion-shaft, substantially as herein described.

45 4. The combination, with the adhesion and supporting axles and wheels of a locomotive, of a frame supported independently of the springs of the locomotive, a shaft journaled in said frame and carrying cranks set at an angle relatively to each other and a pinion, and two concentric rock-shafts arranged one 50 within the other and having arms connected by rods with the cranks on the pinion-shaft, substantially as herein described.

55 5. The combination, with the adhesion and supporting axles and wheels of a locomotive, of a frame supported independently of the springs of the locomotive, two shafts journaled in said frame and each carrying a pinion for engaging a rack-rail, cranks, and parallel rods, whereby the two pinion-shafts are coupled 60 together, and connecting-rods through which motion is transmitted to the cranks on one pinion-shaft for driving both of said shafts, substantially as herein described.

65 6. The combination, with a locomotive and a frame supported independently of the springs thereof, of pinions journaled in said frame and coupled together, and adapted to engage with

a rack-rail, each pinion having an elastic or yielding connection with its shaft, substantially as herein described.

7. The combination, with a railway-vehicle, of a pinion supported independently of the springs of the vehicle and adapted to engage with a rack-rail, the pinion being composed of two or more toothed disks arranged side 75 by side and having an elastic or yielding connection with the shaft, whereby the disks may turn slightly one relatively to another, substantially as herein described.

8. The combination, with the adhesion and supporting axles and wheels of a locomotive, of a frame supported independently of the springs of the locomotive and pinions journaled in said frame and coupled together one in advance of the other, the teeth of the pinions being stepped or set out of line, so that the teeth of one pinion will engage the teeth of the rack-rail slightly in advance of those of the other pinion, substantially as herein described.

9. The combination, with the adhesion and supporting axles and wheels of a locomotive, of a frame supported independently of the springs of the locomotive, pinions journaled in said frame and coupled together, each pinion consisting of two or more toothed disks set with their teeth stepped relatively to each other, and the two pinions being coupled so that the teeth of one are stepped or engage with the rack-rail in advance of the teeth of the other pinion, substantially as herein described.

10. The combination, with the adhesion and supporting axles and wheels of a locomotive, of a frame supported independently of the springs of the locomotive and pinions journaled in said frame and coupled together, each pinion consisting of toothed disks having their teeth stepped one relatively to another, and having an elastic or yielding connection with their 110 shaft, and the teeth of the two pinions being stepped one relatively to another, so that the teeth of one pinion will engage the teeth of a rack-rail slightly in advance of the teeth of the other pinion, substantially as herein described.

11. The combination, with a pinion-shaft and a pinion composed of toothed disks arranged side by side, of flanges between which the disks are confined and one or each of which carries a cylindric brake-drum, substantially 120 as herein described.

12. The combination, with a shaft and a hub or center fast thereon, of a pinion consisting of toothed disks encircling the hub or center and arranged side by side, and springs interposed between the hub or center and the several disks, whereby the several disks are individually enabled to yield circumferentially relatively to the hub or center and to each other, substantially as herein described.

13. The combination, with a shaft and a hub or center fast thereon and having grooved or spring-seats in its periphery, of a pinion composed of toothed disks arranged side by

side upon the hub or center and having notches in their inner circumference opposite the grooves or spring-seats in the hub or center, and springs seated in the hub or center and engaging the notches in said disks, whereby the said disks are enabled individually to yield circumferentially relatively to the hub or center and to each other, substantially as herein described.

10 14. The combination, with the shaft D and hub I, fast thereon and having U-shaped spring-seats g^2 in its periphery, of a pinion composed of toothed disks encircling the hub side by side and having notches g^3 in their inner circumference, and the springs g , of U shape form, fitting the seats g^2 , and having their ends which engage the notches g^3 pro-

15

vided with inward projections g' , which form stops to limit their elasticity, substantially as herein described.

15. The combination, with a rack-rail composed of toothed bars arranged parallel side by side with spaces between them, and a locomotive having a pinion or pinions engaging the rack-rail, of a snow-plow carried by the locomotive and having projections which enter the spaces between the parallel bars of the rack-rail and serve to clear said spaces, substantially as herein described.
